United States Patent Office.

W. P. UHLINGER, OF PHILADELPHIA, PENNSYLVANIA.

Design No. 3,663, dated September 14, 1869.

DESIGN FOR RUSTIC SETTEES.

The Schedule referred to in these Letters Patent and making part of the same.

To all whom it may concern:

Be it known that I, W. P. UHLINGER, of Philadelphia, in the county of Philadelphia, and State of Pennsylvania, have invented a new and original Design for Rustic Settees; and I do hereby declare that the following is a full, clear, and exact description of the same.

The nature of my design is fully represented in the accompanying photographic illustration, to which reference is made.

I claim as my invention—

The design for a rustic settee, as shown.

In testimony that I claim the above, I have hereunto subscribed my name, in the presence of two witnesses.

W. P. UHLINGER.

Witnesses:

DAVID C. FOLWELL,
